UNITED STATES PATENT OFFICE.

AXEL H. WOLYN, OF CHICAGO, ILLINOIS, ASSIGNOR TO ROYAL GAS
LIGHT COMPANY, OF CHICAGO, ILLINOIS, A CORPORATION.

VAPOR-GENERATOR.

SPECIFICATION forming part of Letters Patent No. 760,675, dated May 24, 1904.

Application filed May 22, 1903. Serial No. 158,245. (No model.)

To all whom it may concern:

Be it known that I, AXEL H. WOLYN, a citizen of the United States, and a resident of Chicago, Cook county, Illinois, have invented certain new and useful Improvements in Vapor-Generators, of which the following is a full, clear, and exact description.

The present invention has relation more particularly to that class of vapor-generators 10 designed for use in hydrocarbon lighting and heating systems. In such systems it has heretofore been proposed to vaporize the hydrocarbon (usually gasolene) by passing it through a generator containing porous or granular material adapted to effect a large surface exposure of the hydrocarbon, this generator being subjected to heat in order to effect the vaporization of the hydrocarbon fluid.

An objection incident to the various devices heretofore used in vaporizing or generating gas from gasolene or like liquid hydrocarbon is that the porous, granular, or like material within the generator is apt to become coked, so that its efficiency is impaired 25 and its removal from the generator is effected with much difficulty.

One object of the present invention is to provide for the porous, granular, or like material through which the hydrocarbon is to 30 be passed while being subjected to heat a holder or retaining casing forming, as it were, a "cartridge" that can be quickly placed in position for use and can be readily replaced by a new holder or cartridge without materially delaying the working of the system.

In the preferred form of my invention the removable holder that contains the porous, granular, or like material is held within the generator; but I do not wish the invention to 40 be understood as limited either to the specific form of holder for the porous or granular material or to the specific construction of generator, since these may be modified without departing from the spirit of the invention.

45 A further object of this invention is to provide a generator with a return passage through which the vapor or gas will pass and whereby it will be highly heated before its admixture

with the air and its passage into the delivery-pipe of the system.

With these objects in view the invention consists in the improvement hereinafter described, illustrated in the accompanying drawings, and particularly pointed out in the claims at the end of this specification.

Figure 1 is a view in vertical section through an apparatus embodying my invention. Fig. 2 is a view in vertical section on line 2 2 of Fig. 1. Fig. 3 is a detail view in side elevation of the cartridge-casing.

A designates the supply-pipe whereby the liquid hydrocarbon is delivered to the generator B, this supply-pipe A being preferably provided with a controlling-cock *a* of any suitable character. The generator B is preferably of cast metal and is shown as formed with a chamber *b*, adapted to receive the holder or cartridge-casing C, wherein will be contained the porous or granular material D, to which the liquid hydrocarbon will be delivered by a port *b'*, communicating with the delivery-pipe A. The holder or cartridge-casing C is preferably 65 a tube of brass or like material adapted to receive the granular or porous material D, which material may be retained within the holder or casing C by a plug *d*, of asbestos or like porous material.

Any other suitable form of plug may be used, however, for the end of the holder or casing C. As shown, the end of the holder or casing C is formed with slits *e*, although these are not essential. Preferably, the outer end of the chamber *b* is screw-threaded to receive the correspondingly threaded portion *c'* of the holder or casing C, and, as shown, the outer end of this casing is 75 formed with a head that is squared or otherwise conveniently formed, as at *c'*, to receive a wrench, so that the holder or casing can be conveniently withdrawn from the chamber of the generator B.

Adjacent its outer end the holder or casing C is formed with a series of slits or openings *c'*, through which the hydrocarbon-vapor will pass into a chamber *b'* in the wall of the generator B, and from this chamber *b'* the vapor will pass by a channel *b'* to the port or channel *e* of a valve-casing E, 85 90 95

whence it will pass, through the air-admission pipe F and pipe G, into the delivery-pipe H of the system. As shown, the casing E is provided with a needle-valve E' for regulating the flow of vapor, although manifestly any other suitable form of valve may be used for this purpose, and the stem of this needle-valve E is fitted with a suitable handle e', whereby the valve may be conveniently operated.

From the vapor or gas supply pipe H is tapped a branch pipe K, (preferably provided with a regulating-cock k,) by which gas will be led to the generator-burner M beneath the generator B.

From the foregoing description the operation of my invention will be seen to be as follows, viz: The liquid hydrocarbon admitted by the supply-pipe A will pass by the inner end of the holder or casing C to the porous or granular material contained therein. In practice I have employed fine gravel, brass filings, or like material within the holder or casing C, although manifestly particles of glass, porcelain, intertwined wires, or any other suitable porous or granular material may be used that will serve to effectively distribute the liquid hydrocarbon. A preheating of the generator B will be effected by a torch to secure the initial generation of gas. The gas passing from the chamber b of the generator B will be delivered through the valve-casing E into the pipe G and delivery pipe or main H, carrying with it a suitable quantity of air admitted by the chamber F in manner well understood. After the initial generation of the gas is thus effected a certain amount of gas will pass by pipe K to the generator-burner M, and by means of this burner a continued heating of the generator will be effected.

When the porous or granular material within the holder or casing C becomes coked or clogged after considerable usage, the holder or casing C will be withdrawn and a fresh cartridge—*i. e.*, a fresh holder or casing loaded with granular or porous material—will be inserted in the generator. By this means it becomes unnecessary for the unskilled user of the system to clean the generator, since the cartridges will be supplied to the user in convenient number and may be re-filled at any convenient times.

A further advantage incident to the use of a removable holder or casing for the porous or granular material is that this material may be uniformly and closely packed before the holder or casing is inserted into the generator. In practice it has been found that if pockets or open spaces be allowed within the generator they tend to produce a variable and unequal quality of gas, resulting in a flickering of the burners, that is highly objectionable.

The feature of providing the tubular casing

or cartridge with means whereby it may be withdrawn from the generator-chamber is one of marked advantage, because if the tubular casing were not provided with such means it would be impossible to withdraw it from the generator-chamber, since the coking of the hydrocarbon about the joints of the casing would prevent its withdrawal. By providing the tubular casing with the screw-threaded plug at one end, this plug being the preferable means for effecting the withdrawal of the casing, the turning of the plug necessarily turns and loosens the casing, so that it may be withdrawn by the plug from the generator-chamber.

Having thus described my invention, what I claim as new, and desire to secure by Letters Patent, is—

1. In apparatus of the character described, a cartridge for the vapor-generator comprising a tubular casing having a granular or equivalent filling, said casing being open adjacent its ends for the passage therethrough of vapor and being provided at one end with a head whereby said casing may be turned and having at its opposite end means carried by the casing to prevent the escape of the granular material therefrom.

2. In apparatus of the character described, the combination with a generator provided at one end with a port for admitting liquid hydrocarbon thereto and provided at its opposite end with a port for the discharge of vaporized hydrocarbon therefrom and a removable tubular casing adapted to fit snugly within said generator, said casing having a filling of granular or equivalent material and having openings connecting respectively with the delivery-port and with the discharge-port of the generator-chamber, whereby the vaporized hydrocarbon will be caused to pass through said casing, said casing being provided at its outer end with a head whereby the casing can be withdrawn from the generator-chamber.

3. In apparatus of the character described, the combination of a generator having a horizontally-arranged chamber provided at one end with a port for admitting liquid hydrocarbon thereto and provided at its opposite end with a port for the discharge of vaporized hydrocarbon therefrom, and a removable tubular casing having a filling of granular or equivalent material, said casing being open at the end adjacent the admission-port of the generator-chamber and being provided adjacent the discharge-port of the generator-chamber with a lateral opening and being provided at its outer end with means whereby the casing can be withdrawn from the generator-chamber.

4. In apparatus of the character described, the combination with a generator having a horizontally-disposed chamber provided at its

inner end with a port for admitting liquid hydrocarbon thereto and provided adjacent its opposite end with a port for the discharge of vaporized hydrocarbon therefrom, the outer 5 end of said generator-chamber being formed with an interior screw-thread, a removable tubular casing having a filling of granular or equivalent material and having openings connected respectively with the delivery -port 10 and with the discharge-port of the generator-chamber and having fixed thereto a screw-threaded plug for engaging the threaded outer end of the generator-chamber.

5. An apparatus of the character described, 15 comprising a generator having a chamber provided at one end with a port for the admission of liquid hydrocarbon and provided ad-

jacent its opposite end with a lateral port for the discharge of vaporized hydrocarbon, said generator being provided also with a channel 20 extending lengthwise of said generator from the discharge-port of said chamber to the inner end of the generator and a removable tubular casing located within said chamber and provided with a porous filling, said tubular 25 casing having openings opposite the admission and discharge ports of said chamber and having at its outer end means whereby it may be withdrawn from said chamber.
